By J. C. H. Sturgeon, Atty.

UNITED STATES PATENT OFFICE.

ROBERT C. STEVENS, OF ERIE, PENNSYLVANIA, ASSIGNOR TO SKINNER ENGINE COMPANY, OF ERIE, PENNSYLVANIA, A CORPORATION OF PENNSYLVANIA.

STEAM-SUPERHEATER.

1,102,361.

Specification of Letters Patent.

Patented July 7, 1914.

Application filed February 10, 1913. Serial No. 747,368.

To all whom it may concern:

Be it known that I, ROBERT C. STEVENS, a citizen of the United States, residing at Erie, in the county of Erie and State of Pennsylvania, have invented certain new and useful Improvements in Steam-Superheaters; and I do hereby declare the following to be a full, clear, and exact description of the invention, such as will enable other skilled in the art to which it appertains to make and use the same, reference being had to the accompanying drawings, and to the letters of reference marked thereon, forming part of this specification.

My invention relates to steam-super-heaters and has for its object the combining of a super-heater with a horizontal tubular steam boiler in such a manner that a portion of the products of combustion may be deflected from the combustion chamber, and before they have passed through the boiler flues into the super-heating chamber, and, in carrying out the object of my invention to so locate the point of deflection that the products of combustion from the combustion chamber will not be so intense as to burn out the super-heater tubes.

The features of my invention are herein-after set forth and fully explained, and are illustrated in the accompanying drawings, in which:

Figure 1, is a vertical central section of the boiler setting and super-heater chamber walls showing a steam boiler and super-heater apparatus mounted therein according to my invention. Fig. 2, is a transverse section of the same, on the line $x-x$, in Fig. 1.

In these drawings A, indicates a steam boiler, A', indicates the heating furnace therefor, a, indicates the grate bars, a', indicates the back fire-wall of the furnace chamber A', A², indicates the heat chamber, back of the fire-wall a', B, indicates the covering over the top of the boiler, B', indicates the smoke-chamber, at the front end of the boiler A, B², indicates the draft-flue leading to the usual breeching B³, which is

connected with the smoke-stack (not shown), which parts are of usual and ordinary construction in the setting of tubular boilers of the type shown in Fig. 1. Transversely across the rear end of the heat-chamber A², I construct a super-heater chamber C, in which chamber I place a super-heating apparatus D. Through the rear wall a², of the heat-chamber A², I make an opening C', into the super-heater-chamber C. From the upper end of this super-heater-chamber C, I provide a smoke-flue E, which is connected to the breeching B³, by means of a flue E'. The draft-flue B², is provided with a damper mechanism b, and the smoke-flue E', is also provided with a damper mechanism e. In the super-heater-chamber C, I preferably place baffle-walls c, and c', the baffle-wall c, extending upwardly from the bottom of the chamber C, toward the upper portion thereof and the wall c', extending upwardly from the bottom of the chamber C, to the top, c², of said chamber C, and having an opening c³, in the lower part thereof.

In operation, when it is desired to use the super-heater D, the damper e, in the flue E', is opened, which permits a portion of the heated gas in the heat-chamber A², to be drawn through the opening C', into the chamber C, and upwardly over the upper end of the baffle-wall c, and downwardly through the opening c³, and then upwardly into the flues E, and E', to the breeching B³, and thence to the smoke-stack.

It will be obvious that the amount of heat taken into the chamber C, can be regulated as may be desired by means of the dampers b, and e.

Having thus fully described and illustrated my invention, what I claim as new and desire to secure by Letters Patent is:

The combination in an apparatus of the character described, of a horizontal tubular boiler, a furnace thereunder to receive fuel to be burned, a transverse fire-wall, a wall adjacent to the rear end of said boiler having an opening therethrough below the up-

per edge of said fire-wall and forming a combustion chamber at the rear end of said tubular boiler, vertical side and end walls forming a chamber against said rear wall, 5 a drum secured and inclosed within the upper portion of said chamber, super-heater tubes secured in the shell of said drum and depending therefrom, and a draft flue lead-

ing from said chamber above said drum, substantially as set forth.

In testimony whereof I affix my signature in presence of two witnesses.

ROBERT C. STEVENS.
